UNITED STATES PATENT OFFICE.

BEARL E. COLBURN, OF GREEN BAY, WISCONSIN, ASSIGNOR TO AERIAL INSULATOR CO., INC., OF GREEN BAY, WISCONSIN, A CORPORATION OF WISCONSIN.

INSULATOR FOR RADIOANTENNAE.

Application filed March 22, 1928. Serial No. 263,750.

This invention pertains to improvements in radio antennæ, and more particularly to a head-piece for insulating and attaching the antenna wires to any form of suitable support.

The invention has primarily for its object to provide a simple, inexpensive, and efficient insulator head applicable to any type of vertical or horizontal antenna, as for instance those commonly termed "straight-line," "cage," or "umbrella" types.

Incidental to the foregoing, a more specific object is to provide a simple and novel structure of insulator, wherein the attaching means is efficiently insulated from the antenna receiving member.

Another object is to provide an insulator of the foregoing character, with means capable of attachment to any and all types of supports, such as a pole, hook, or tree.

A still further object resides in the provision of a novel insulated antenna receiving member, which permits the construction of the alternative types hereinbefore enumerated.

In the installation of conventional types of radio antennæ, supported upon a mast or pole, it is common practise to provide guy wires, which are necessarily conductors of a high frequency radiation, for bracing the supporting poles or masts. Due to the close proximity of these wires to the antenna, it is necessary to provide and install a great number of insulating blocks at both ends of the wire, in order to prevent grounding and consequent detraction from the efficiency of the antenna by inductance.

It is therefore a further object of the present invention to overcome the foregoing objections and provide a single insulator for attachment to the pole or mast and adapted to receive any number of guy wires, thus eliminating the necessity of installing individual insulators between the guy wires and pole.

With the above and other objects in view, which will appear as the description proceeds, the invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings is illus-

trated one complete example of the physical embodiment of the present invention constructed according to the best mode so far devised for the practical application of the principles thereof.

Figure 1 is a transverse section through an insulator constructed in accordance with the present invention, the same being taken on line 1—1 of Figure 2.

Figure 2 is an elevational view.

Figure 3 illustrates the present invention applied to what is commonly termed a cage type of antenna, and

Figure 4 illustrates the invention applied to an umbrella type antenna, or a mast for receiving any other conventional type of horizontal antennæ.

Referring now more particularly to the accompanying drawings, the numeral 1 designates an annular plate constructed of any suitable insulating material, and provided centrally of its outer face with an annular recess 2 for the reception of the head 3 of a threaded stud 4. The peripheral edge of the plate 1 adjacent its outer face, is provided with a shoulder 5, rearwardly of which is a second annular shoulder 6 adapted to receive an inwardly projecting flange 7 of the antenna receiving ring 8, which ring is provided with a rearwardly projecting offset 85 apron 9, provided with a plurality of spaced holes 10 for the reception of the antenna or guy wires.

At spaced intervals the flange 7 of the ring 8 is provided with slots 11 for the reception of screws 12 threaded into the insulating plate 1, the heads of the screws engaging the shoulder 5, of the insulating block, and flange 7, to retain the ring in tight engagement with the insulated block.

As best shown in Figure 1, the block 1 is provided with a recess 13 on its rear face, for the reception of the nut 14 threaded on the stud 4 to clamp the same to the block 1. The head 3 of the stud 4 is provided with an ear 15, having an opening 16, for the purpose to be hereinafter described.

While the present invention has many applications, those which are most characteristic have been illustrated. Figure 3 shows the insulator utilized in a cage type antenna, wherein two insulators are employed, and the antenna wires W are strung from one to the other. In this form, the insulators are fastened to any suitable support by means of the

hooks H, received in the openings 16 provided in the studs 15, although it will be obvious that the studs may be fastened to any support, such as a tree or mast, by means of 5 wires or cables.

In that application of the invention illustrated in Figure 4, which is commonly termed an umbrella type of antenna, the stud 4 is threaded into the top of a pipe or mast P, and 10 in this instance the antenna wires W secured to the ring 8, are fastened at their lower end to a roof or other support for the mast. In this form the lead in wire S, to the receiving set, is secured to the ring 8. It will also be appreciated that this arrangement can be utilized as a support for any type of horizontal antenna, in which instance the antenna would be connected to the ear 16, and the lead-in wire taken off of the antenna instead of the ring 8. 15 However, in both instances, the lower ends of the wires W are insulated from the support by blocks I to prevent grounding.

From the foregoing description, it will be seen that a very simple, inexpensive and efficient insulator has been provided, which may be readily applied to antennæ of all types. It will also be noted that the construction of the insulating block, wherein the head 3 of the stud 4 is received in a recess and separated 20 from the screws 12 and the flange 6 by a projecting portion of the insulating block, serves to prevent the passing of current from the antenna ring to the stud, or vice versa. This is also true of the rear face of the insulating plate, as the nut 14 is recessed into the plate. It will be appreciated that a sufficient amount 25 of insulating material has been provided in the plate 1 to properly insulate the antenna receiving member from the attaching stud.

40 I claim:—

1. An insulator for radio antennæ comprising a plate formed of insulating material, a threaded stud secured centrally of said plate for attachment to a suitable support, a ring 45 secured to the periphery of said plate and spaced from said stud, and an off-set apron

projecting from said ring and provided with spaced wire receiving apertures.

2. An insulator for radio antennæ comprising a plate provided with a central opening 50 and recesses in its opposite faces and in alignment with said opening, a threaded stud positioned in said opening, a head carried by the stud and received in one of said recesses, a nut threaded on said stud and positioned in the other of said recesses, and a ring secured to the periphery of said plate and provided with spaced wire receiving apertures.

3. An insulator for radio antennæ comprising an annular plate formed of insulating material and provided with an annular shoulder, a threaded stud secured centrally of said plate, a ring surrounding said plate and provided with an inwardly projecting flange engaging said shoulder, and means engaging 60 said flange for securing the same to said plate, said ring being provided with spaced wire receiving apertures.

4. An insulator for radio antennæ comprising a plate formed of insulating material and 70 provided with a central opening and recesses on its opposite faces aligned with said opening, the periphery of said plate being provided with an annular shoulder, a threaded stud positioned in said central opening and 75 having a head received in one of said apertures, an ear projecting from said head and provided with an aperture, a nut threaded on said stud and received in the other of said recesses for securing said stud to the plate, a ring surrounding the periphery of said plate and provided with an inturned flange engaging said shoulder, screws threaded into said plate and provided with heads engaging said flange to lock the same against the peripheral 80 shoulder formed in said plate, and an offset apron projecting from said plate and provided with spaced wire receiving apertures.

In testimony that I claim the foregoing I have hereunto set my hand at Green Bay, in 90 the county of Brown and State of Wisconsin.

BEARL E. COLBURN.
